CLAIM

I claim the ornamental design for a seat, as shown and described.

DESCRIPTION

FIG. 1 is a perspective view of the first embodiment of a seat showing the new and original design;

FIG. 2 is a side elevational view of the first embodiment with the opposite end view being a mirror image thereof;

FIG. 3 is a top plan view of the first and second embodiments thereof;

FIG. 4 is an end elevation view of the first embodiment with the opposite end view being a mirror image thereof;

FIG. 5 is a side elevational view of the second embodiment with the opposite side view being a mirror image thereof;

FIG. 6 is an end elevation view of the second embodiment with the opposite end view being a mirror image thereof; and,

FIG. 7 is a bottom plan view of the first and second embodiments thereof.
